UNITED STATES PATENT OFFICE.

MARY E. DAVISON PLUMLEY, OF WASHINGTON, DISTRICT OF COLUMBIA.

DESIGN FOR A CAMPAIGN-CAP.

SPECIFICATION forming part of Design No. 25,987, dated September 8, 1896.

Application filed August 8, 1896. Serial No. 602,202. Term of patent 31 years.

To all whom it may concern:

Be it known that I, MARY E. DAVISON PLUMLEY, a citizen of the United States, residing at the city of Washington, in the District of Columbia, have invented and produced a new and original Design for a Campaign-Cap; and I do declare the following to be a full, clear, and exact description of the same, reference being had to the accompanying drawing, forming a part thereof.

My design relates to a campaign-cap designed more especially for political clubs, but which may be used individually; and the leading feature consists in a cap of the shape and configuration shown in the accompanying drawing, the top of the crown being provided with sixteen white petals radiating from a single yellow circular center, thus representing a sixteen-leaf daisy.

In the accompanying drawing the figure represents a perspective view of a cap constructed in accordance with my design.

In the said drawing the reference-letter A designates the crown of the cap, B the top of the crown, and C the visor. The crown ²⁵ of the cap has its top provided with sixteen radiating petals D, all springing from a circular center E, representing a sixteen-leaf daisy. The top of the crown may be formed of open or net work of any suitable material ³⁰ or of any other material contrasting with the petals and circular center, so that said petals and center will be brought prominently in view.

What I claim is—

The design for a campaign-cap substantially as herein shown and described.

In testimony whereof I affix my signature in presence of two witnesses.

MARY E. DAVISON PLUMLEY.
